UNITED STATES PATENT OFFICE.

WILLIAM H. COTTON, OF SALEM, NEW YORK.

COVER FOR SAP-BUCKETS.

1,228,096.

Specification of Letters Patent.

Patented May 29, 1917.

Application filed October 22, 1915. Serial No. 57,830.

To all whom it may concern:

Be it known that I, WILLIAM H. COTTON, a citizen of the United States, residing at Salem, in the county of Washington and

5 State of New York, have invented certain new and useful Improvements in Covers for Sap-Buckets, of which the following is a specification, reference being had therein to the accompanying drawing.

10 This invention relates to covers for sap buckets, and has for its principal object the production of a simple and efficient cover which may cover the sap bucket while the sap is being drawn from the tree, so as to prevent any refuse whatever from accidentally falling into the bucket.

Another object of this invention is the production of a cover for sap buckets which is adapted to cover the bucket when desired 20 but which may be easily swung to an open position for allowing free access to the bucket or allow the bucket to be removed, this cover being provided with a very simple and efficient means for automatically and 25 positively retaining the same in an open position.

Another object of this invention is the production of a spout having a simple and efficient means for retaining a hook thereon, 30 whereby the cover may be pivotally and detachably secured thereto while the hook is constructed to carry a bucket so that the entire structure may be easily supported upon a tree.

35 With these and other objects in view, this invention relates to certain novel combinations, constructions, and arrangements of parts as will be hereinafter fully described and claimed.

40 In the accompanying drawing:

Figure 1 is a detailed perspective view of the cover as constructed in accordance with this invention, showing the same carried by the spout, and illustrating the manner in 45 which the same is used.

Fig. 2 is a detailed perspective view of the inner portions of the cover, showing the same swung to an open position, and illustrating the same in use.

50 Fig. 3 is a top plan view of the cover for sap buckets.

Fig. 4 is a central longitudinal section through the cover, showing the spout in longitudinal section.

55 Fig. 5 is a section taken on the line 5—5

of Fig. 3 looking in the direction of the arrow.

Fig. 6 is a detailed perspective view of the spout and hook carried thereby in dotted lines.

Referring to the accompanying drawing by numerals it will be seen that the device is adapted to be used in connection with any tree as disclosed at 1. The spout 2 in combination with which the cover is adapted to be 65 used, tapers toward its inner end adjacent which is formed the aperture 3, so that when the inner end 4 of the spout is carried within the tree 1, as shown in Fig. 1, the sap may be passed through the aperture 3 into the in- 70

terior of the spout 2. This spout 2 is pro- 75 vided with the guide portion 5 which is adapted to guide the sap which is passed into the interior of the spout 2 into the bucket. The spout 2 is provided with an in- 80 tegral shoulder 6 upon its upper portion ad- 85 jacent which is formed the lug 7. A hook 8 is adapted to be passed over the end 4 of the spout 2 so as to allow its open portion 9 to pass over the lug 7, at which time it may be 90

swung so as to depend from the spout 2, whereby it will be possible to retain the shoulder 6 and lug 7. This spout is also pro- 95 vided with registering openings 10 formed adjacent the shoulder 6, for purposes to be 100 hereinafter set forth.

The cover 11 is formed from a blank and comprises a body having a central rib 12. This rib diverges from its forward portion toward its rear portion and its height in- 105 creases toward its rear portion, as clearly shown in Figs. 1 and 4. From each side edge of the body 11 there is formed depend- 110 ing flanges 13, while the forward edge of the body 11 is fringed as shown at 14 to ex- 115 tend to the diagonal edge 15 extending to the perpendicular flange 13, whereby the water may pass very rapidly therealong so as to fall from the side flanges without danger of being blown or running back 120 under the cover and falling into the bucket 16. It will be noted that the width of the cover is greatest at its forward portions, and, therefore various sized buckets may be 125 accommodated, while the rib 12 will consti- 130 tute a water guide as well as providing suf- 135 ficient resiliency for the cover 11 for allowing the same to slightly yield for accommo- 140 dating larger sized buckets when necessary. 145

This rib 12 is provided with a cut-out pocket 150

portion 17 communicating with the opening 18, so that this opening 18 will form the gripping ears 19. Openings 20 are also formed in alinement adjacent the pocket 17, 5 so that the cover may be pivotally secured to the spout 2 by passing a cotter pin 21 through the openings 20 formed in the rib 12 and the openings 10 formed in the spout 2. It is of course, obvious that when so de- 10 sired the cotter pin may be withdrawn so as to allow the cover to be easily detached or removed from the spout 2.

When the device is in use the spout 2 is adapted to be driven into a tree. At this 15 time the hook is of course carried by the spout so that when the spout has been secured, the bucket 16 may be positioned upon the hook as shown in Fig. 2. The cover for the sap bucket 16 may then be positioned 20 upon the upper portions of the bucket so as to allow the openings 20 to register with the openings 10 for allowing the cotter pin 21 to be passed therethrough. The side flanges 13 will then overhang the side 25 portions of the bucket 16, and therefore, since the cover fits snugly upon the upper portions of the bucket any danger of dirt or other refuse passing or falling into the bucket is eliminated. The cover may remain 30 in the closed position shown in Fig. 1 until the bucket is filled. When, however, it is desired to have access to the interior of the bucket or to remove the same from engagement with the hook 8, the cover 11 may be 35 swung upwardly to the position shown in Fig. 2. This action will cause the gripping ears 19 to be spread apart as the body portion of the spout 2 passes through the cut-out portions 18. As soon as these clamped 40 ears have passed around the side portions of the spout 2 they will again spring to their normal positions as disclosed clearly in Fig. 3, at which time the spout will be extending through the pocket 17, and since the 45 gripping ears 19 will engage the lower portions of the spout 2 the cover will be positively retained in the position shown in Fig. 2. When, however, it is desired to again position the cover upon the sap 50 bucket they may be gripped and then swung downwardly so as to cause the spout to move from the pocket 17 and pass the gripping ears 19, at which time the cover will assume the position shown clearly in Fig. 1. 55 It is, of course, obvious that the resilient construction of the gripping ears 19 will allow the spout to pass easily thereby when

sufficient pressure is brought to bear thereon, but their structure is of sufficient strength as to prevent the cover from accidentally 60 swinging to a closed position when it is desired to retain the same in an open position.

From the foregoing description it will be seen that a very simple and efficient cover 65 for a sap bucket has been produced wherein the cover is adapted to be used in combination with any suitable spout, but preferably the one herein disclosed so as to form a cover for preventing the passage of refuse 70 into the sap bucket, while a simple and efficient means has been provided for retaining the cover against accidental displacement from the cover portions of the bucket and also for retaining the cover in an open 75 position as the occasion may require.

What is claimed is:

1. In a cover of the class described, the combination of a body having a central up-standing rib formed centrally thereon, said 80 rib being provided with alined openings, a spout having alined openings, means passing through the openings in said rib and the openings in said spout for pivotally mounting said body upon said spout, said 85 body being adapted to be normally carried in a horizontal plane, and means engaging said spout as the cover is raised for releasably retaining said body in a vertical position. 90

2. In a cover of the class described, the combination of a body having a central up-standing rib formed centrally thereon, said rib being provided with alined openings, a spout having alined openings, means passing through the openings in said rib and the openings in said spout for pivotally mounting said body upon said spout, said body being adapted to be normally carried in a horizontal plane, said rib being provided in 100 its top portion with a pocket and with a cut-out portion communicating with said pocket, thereby forming inwardly extending spout gripping ears, said body being adapted to be swung upwardly so as to cause 105 said ears to be spread as said spout passes into said pocket, after which action said ears will spring to their normal positions beneath said spout for releasably retaining said body in a vertical position. 110

In testimony whereof I hereunto affix my signature.

WILLIAM H. COTTON.
